UNITED STATES PATENT OFFICE

LOUIS V. ARONSON, OF NEWARK, NEW JERSEY

DESIGN FOR A LAMP STAND OR SIMILAR ARTICLE

Application filed April 10, 1930. Serial No. 35,203. Term of patent 14 years.

To all whom it may concern:

Be it known that I, LOUIS V. ARONSON, a citizen of the United States, residing at Newark, in the county of Essex and State of New Jersey, have invented a new, original, and ornamental Design for Lamp Stand or Similar Article, of which the following is a specification, reference being had to the accompanying drawing, forming part thereof, wherein:

Figure 1 is a plan view of a lamp stand as constructed in accordance with my invention; and

Fig. 2 is a side elevational view of the lamp stand shown in Fig. 1.

I claim:

The ornamental design for a lamp stand or similar article substantially as shown.

LOUIS V. ARONSON.
